LOW-PRESSURE MULTIPULL PAPER
BURSTER GUNAlfred F. Langos, Chicago, Ill., assignor to Lang-
son Manufacturing Co., Chicago, Ill., a corpora-
tion of Illinois

Application July 5, 1950, Serial No. 172,053

1 Claim. (Cl. 46—195)

1
The present invention relates to a toy of the general type wherein a slidably supported member is cocked against the action of a spring and released to act upon an object carried in the toy.

More particularly, the invention relates to a paper bursting toy of the type wherein a movable member is adapted to be cocked and driven by a strong coil spring for developing sufficient air pressure to burst a strip of paper carried in the toy.

In toys generally of the type set forth above, it is essential that the coil spring driving the movable member be sufficiently strong so that the toy be capable of performing its designed function, such as bursting a strip of paper, shooting a cork, or squirting a stream of water. Therefore, a considerable amount of strength is required on the part of an operator, in order to actuate such guns. Due to this characteristic, guns of this type are necessarily restricted in their use to older children having sufficient strength; but because paper burster guns are completely harmless and are desirable playthings, the need for a gun of this general type that could be used by younger children, has long been recognized. In the past, efforts to make such a gun have been centered around extension of the actuating or trigger lever. These efforts have proven unfruitful in that elongation of the trigger lever failed to provide the necessary leverage in a unit sufficiently small to be grasped by younger children, and spoiled the configuration of the gun, thus making it undesirable to the children. Further, the actuating mechanisms of known air pressure developing paper bursting of this type generally utilize linearly movable parts which require certain types of housing configurations providing sufficient space for movement of the parts. In order to modify the configuration of the housing, it was first necessary to provide a compact actuating mechanism. Thus, the need for a relatively compact paper burster actuating mechanism, and particularly for a compact paper burster actuating mechanism including an automatically operating paper feed means, has long been recognized.

It is therefore one object of the present invention to provide an improved actuating mechanism requiring only a small amount of strength, for a toy having a slidable member driven by a strong biasing means for acting upon an object carried in the toy.

Another object of the invention is to provide an improved rotary actuating mechanism for use in air pressure developing paper bursting toys

having confined configuration or small housings.

5 A further object of the invention is to provide a paper bursting toy having an improved rotary paper feed mechanism therein.

A feature of the invention is the provision of an improved toy actuating mechanism for cocking a spring driven member against the action of a strong spring in a plurality of cocking steps 10 requiring only sequential operation of the actuating means and little strength.

Another feature of the invention is the provision of a novel paper bursting toy having a rotary cocking member for actuating the toy, and for 15 automatically feeding paper during the cocking movement.

Other objects, features and many of the attendant advantages of this invention will be appreciated readily as the same becomes understood by reference to the following detailed description, when considered in connection with the accompanying drawings, wherein:

Fig. 1 is a sectional view of a paper bursting toy gun incorporating the novel actuating mechanism, and showing the mechanism in one of its operative positions;

Fig. 2 is a sectional view of the gun illustrated in Fig. 1, and showing the novel actuating mechanism in a second of its operative positions;

Fig. 3 is a cross sectional view of a rotary, cocking member comprising a part of the novel toy actuating mechanism; and

Fig. 4 is a fragmentary view showing the cooperation of the novel rotary cocking member with the movable air pressure developing member of 35 the gun shown in Fig. 1.

In practicing the invention, a paper bursting toy is provided, having a movable piston and piston rod member adapted to be cocked and released for bursting a strip of paper automatically fed past and sealed over a cylinder in which the member is seated. The piston and piston rod member is cocked against the action of a powerful coil spring by a ratchet wheel rotatably mounted on the toy, and having a number of 40 engaging pins spaced about the outer periphery of one of its faces, which are lesser in number than the number of teeth in the ratchet wheel. The ratchet wheel is so positioned relative to the piston and piston rod member, that the engaging pins releasably engage and cock the member in steps during a plurality of cocking movements of a trigger operatively connected to the teeth of the ratchet wheel. Automatic paper feeding is provided by a plurality of paper feed pawls spaced about the periphery of the ratchet

wheel, one of which engages the paper during the cocking movement of the member.

Referring now to Fig. 1, a paper bursting toy gun constructed in accordance with the invention is shown. The gun includes a housing 11 having a forward barrel portion, a breech portion including a paper chamber 12 having a paper guideway 13 and 14 leading from it, and a pistol grip portion 16, all of which are cast integral in two mating parts and joined together by a plurality of rivets.

Secured in chamber 12, is a roll of feedable paper 17 which is led from chamber 12 through paper guideway 13, across an aperture 18 formed therein, rearwardly through paper guideway 14, and is discarded to the rear of the gun. Cooperating with paper 17 to burst the same, is a paper bursting means including aperture 18, and an open ended cylinder 19 slidably seated in a semi-cylindrical cavity formed in the forward breech portion of housing 11. Slidable cylinder 19 has a centrally apertured rubber grommet 21 fitted thereon which normally seals paper 17 over aperture 18, and slidably seats a movable member comprising a piston 22 fixed to a piston rod 23, and driven by a coil spring 24. Piston rod 23 has a notch 26 cut midway its length which is bounded on its rearward side by an enlarged piston rod portion 27, the purpose of which will be appreciated more readily hereinafter, and slidably supported in housing 11 substantially in the center thereof, as is shown in Fig. 3.

The movable member comprising piston 22 and piston rod 23, is cocked by a novel actuating mechanism including a trigger 28 pivotally supported on housing 11 by rivet 29, and having an integral lever extension 30 acted against by a return spring 31. Pivotally supported on lever extension 30, is a finger link 32 having a spring 33 biasing it into engagement with a rotatable cocking member having a plurality of primary engaging means spaced about its periphery, comprising a ratchet wheel 34. Ratchet wheel 34 is rotatably secured to housing 11 by pivot pin 35, as can best be seen in Fig. 3, and is disposed to one side of piston rod 23. Secured to the outer periphery of one surface or side of ratchet wheel 34 are a plurality of secondary engaging means comprising piston rod engaging lugs 37 which are lesser in number than the number of teeth in ratchet wheel 34, and, if desired, may be a sub-multiple of the number of teeth. Each of the lugs 37 is positioned to selectively engage piston rod portion 27 to cock piston rod 23 in a plurality of steps, upon sequential operation of trigger 28, and has a feed pawl 38 fixed thereto which cooperates with the upper surface of paper guideway 14 to feed an unbroken portion of paper between rubber grommet 21 and aperture 18 during the cocking movement of piston rod 23. To prevent reverse rotation of ratchet wheel 34 between successive pulls of trigger 28 by reason of the action of coil spring 24, a hooked stop 39 is pivotally mounted on housing 11 by rivet 41, and is biased into engagement with the primary engaging teeth of ratchet wheel 34 by a spring 42.

In operation, upon pulling trigger 28 rearwardly to the position shown in Fig. 2, spring biased finger link 32 engages ratchet wheel 34 and rotates it one step. Simultaneously with the rotation of ratchet wheel 34, stop 39 slides into the next succeeding tooth of ratchet wheel 34, and operates as a stop to prevent reverse rotation of the ratchet wheel upon hooked link 75

32 releasing its hold. At the end of the cocking stroke of trigger 28, coiled spring 31 co-operating with lever extension 30 returns trigger 28 to the position shown in Fig. 1, simultaneously sliding link 32 back one step to engage a new tooth in ratchet wheel 34. As is best seen in Fig. 4, upon ratchet wheel 34 being rotated, the uppermost of lugs 37 comes into engagement with the enlarged portion 27 of piston rod 23. Thereafter further rotation of ratchet wheel 34 serves to cock piston rod 23 against the action of coil spring 24 one step. Between each step, hooked link 32 is released from engagement with ratchet wheel 34 for the purpose of obtaining a new hit; however, stop 39 prevents piston rod 23 from driving the ratchet wheel in the reverse direction. A succeeding cocking stroke of the trigger, cocks piston rod 23 one step further, and the operation is again repeated until the uppermost lug reaches the position shown at dotted lines, at which instant the piston rod 23 is released to the action of the coil spring 24 to burst the paper. Thus, by reason of the invention, it is possible to cock the movable member of a toy against its biasing spring in steps; thereby allowing the necessary total energy required to actuate the toy to be distributed through a plurality of successive pulls. This feature is provided without impairing, in any manner the desired configuration of the toy, and is ideally suited for younger children. Further the invention provides an improved, rotary actuating mechanism for transferring the movement of the trigger of an air pressure developing paper bursting toy to the toy air pressure developing, paper bursting means. By reason of this feature, the toy is simplified, and is more easily packaged in a small housing.

Concurrently with the cocking of piston rod 23, the feed pawl 38 on the uppermost of lugs 37 engages paper 17, pressing the same against guideway 14 and forcing it rearwardly to automatically provide an unbroken portion of paper between the end of cylinder 19 and aperture 18. Thus, the rotary actuating mechanism can be modified to provide an improved automatically operating paper feed mechanism requiring little or no additional space.

In operating the gun, trigger 28 is pulled rearwardly. This movement is transmitted through link 32 operatively connected to rotary ratchet wheel 34, rotating ratchet wheel one step and simultaneously advancing stop 39 one step. Rotation of ratchet wheel member 34 causes a lug 37 to engage piston rod 23 pulling it rearwardly. Due to the friction between piston 22 and cylinder 19, cylinder 19 is moved rearwardly to lift grommet 21 from paper 17, and allowing a paper feed pawl 38 to advance an unbroken portion of paper in front of aperture 18. After only a short travel, a pin 43 in housing 11 contacts a lip 44 extending downwardly from cylinder 19 and prevents further rearward movement of the cylinder. Upon the piston rod being released by lug 37 to the action of coil spring 24, the friction between piston 22 and cylinder 19 causes these two members to drive forward concurrently until rubber grommet 21 contacts paper 17 and the surface of guideway 13 in which orifice 18 is formed. This movement causes the cylinder to form an airtight seal over paper 17 so that further forward movement of piston 22 builds up air pressure, and results in rupturing the paper with a loud report.

Thus, the invention provides an actuating mechanism for a toy having a moving member to

cock against a strong driving spring which requires only a small amount of strength to operate. The invention further provides a rotary actuating mechanism for transmitting the motion of an air pressure paper bursting toy actuating trigger to the air pressure developing means, and which can be contained within a small toy housing. Further, by properly designing the toy housing and mounting paper feed means on the rotary cocking member comprising a part of the invention, a mechanism for performing the dual function of actuating the toy and automatically feeding paper, can be readily provided.

Other modifications and variations will be suggested to one skilled in the art, in the light of the above teachings. It is therefore to be understood that changes can be made in the embodiment of the invention disclosed which are within the full intended scope of the invention as defined by the appended claim.

I claim:

A paper bursting toy gun including in combination a housing having a paper guideway, feedable paper carried in said guideway, means for bursting said paper including a piston rod movable relative to said housing and adapted to be cocked and released for bursting said paper, trigger means for actuating said toy, means operatively connecting said trigger means to said piston rod to cock and release the same to burst said paper, last mentioned means including a ratchet wheel rotatably mounted on said housing and having a plurality of pins spaced about the

15
